TRAFFIC MARKER FOR HIGHWAYS OR THE LIKE

Joseph G. Gokey, Box 384, Oshkosh, Wis.

Filed Aug. 21, 1961, Ser. No. 66,427

Term of patent 7 years

(Cl. D72—1)

Fig. 1

Fig. 2

Fig. 3

Fig. 4

FIG. 1 is a top plan view of a traffic marker for highways or the like showing my new design.

FIG. 2 is a front elevation thereof.

FIG. 3 is a side elevation thereof as seen from the right of FIG. 1.

FIG. 4 is a bottom plan view thereof.

I claim:

The ornamental design for a traffic marker for highways or the like, as shown.
